UNITED STATES PATENT OFFICE.

VICTOR VIVAUDOU, OF NEW YORK, N. Y.

DESIGN FOR A BOTTLE.

49,291.

Specification for Design. Patented June 27, 1916.

Application filed April 17, 1916. Serial No. 91,803. Term of patent 7 years.

To all whom it may concern:

Be it known that I, VICTOR VIVAUDOU, a citizen of France, residing at the borough of Manhattan, in the county, city and State of New York, have invented a new, original, and ornamental Design for a Bottle, of which the following is a specification, reference being had to the accompanying drawing, forming part thereof.

I claim:

The ornamental design for a bottle as shown.

VICTOR VIVAUDOU.
